UNITED STATES PATENT OFFICE

154,387

DESIGN FOR A CASING FOR METALWORKING MACHINE FOR WORKING ON ELONGATED STOCK

Robert A. Johnson, Longmeadow, Mass.

Application October 22, 1947, Serial No. 142,093

Term of patent 3½ years

(Cl. D54—14)

To all whom it may concern:

Be it known that I, Robert A. Johnson, a citizen of the United States, residing at Longmeadow, in the county of Hampden and Commonwealth of Massachusetts, have invented a new, original, and ornamental Design for a Casing for Metalworking Machine for Working on Elongated Stock, of which the following is a specification, reference being had to the accompanying drawings, forming part thereof.

Fig. 1 is a plan view of a casing for metalworking machine for working on elongated stock showing my new design;

Fig. 2 is a side elevational view of the design shown in Fig. 1;

Fig. 3 is a rear elevational view of the design shown in Figs. 1 and 2; and

Fig. 4 is a front elevational view of the design shown in Figs. 1, 2 and 3.

The opposite side of the casing is the same as that illustrated.

I claim:

The ornamental design for a casing for metalworking machine for working on elongated stock, as shown and described.

ROBERT A. JOHNSON.
